UNITED STATES PATENT OFFICE.

ZIBA HICKMAN AND JOHN C. HERBINE, OF READING, PENNSYLVANIA.

BILLIARD-CUE.

No. 830,070.

Specification of Letters Patent.

Patented Sept. 4, 1906.

Application filed February 21, 1906. Serial No. 302,161.

To all whom it may concern:

Be it known that we, ZIBA HICKMAN and JOHN C. HERBINE, citizens of the United States, residing at Reading, in the county of Berks and State of Pennsylvania, have invented new and useful Improvements in Billiard-Cues, of which the following is a specification.

This invention relates to improvements in billiard-cues, and the object is to provide a cue in which the tip may be readily removed and replaced by another.

A further object is to overcome the splitting of the cue-end, which is of frequent occurrence in the ordinary construction.

Another object is the insuring against the use of a private cue by others. With our present construction the ferrule containing the tip may be readily removed from the cue when not in use and conveniently carried in the pocket, as the frequent removal of the ferrule does not affect the position of the tip.

The invention is more fully described in the following specification and clearly illustrated in the accompanying drawings, in which—

Figure 1 is an elevation of the end of our cue. Fig. 2 is a vertical central sectional view thereof, and Fig. 3 shows the parts ready to be assembled. The numeral 1 designates the body of the cue. This body portion is reduced at its smaller extremity and a screw-thread 2 is formed thereon. A central conical lug 7 is also formed on the end.

The numeral 4 designates a tapered ferrule, screw-threaded internally at its larger end and adapted to screw onto the tapered reduced end of the body portion 1 and seat against the shoulder 3, formed thereon by reducing said end. This ferrule is formed with an external circumferential bevel 5 at its smaller end, reducing the thickness of the metal at that point. This is done to prevent accidental cutting of the cloth on the table. This screw-threaded end of the cue enters the ferrule approximately one-half of its length.

The numeral 6 designates the tip, which may be made of leather, cork, or other suitable semi-elastic material. This tip approximates the internal dimension of the smaller end of the ferrule 4 and is inserted therein from the larger or inner end. When the tip has been so placed, the ferrule is screwed onto the cue, and this action will force the tip out of

the smaller end until it has assumed its proper position and the end of the ferrule rests normally against the shoulder 3, the lug 7 tending to spread the lower end of the tip and insure a snug fit in the ferrule. The outer end of the tip is then dressed, and the cue is complete. Inasmuch as the tip rests normally against the end of the body portion of the cue, the effect of the blow received by striking a billiard-ball is conveyed directly to the cue, the ferrule in its intermediate position acting merely as a retainer for the tip and insuring its rigidity. When the tip is worn or otherwise becomes useless, its removal and replacement by a new one is easily accomplished.

By means of our device the life of a cue is prolonged indefinitely and the annoyance and loss of time spent in securing tips to the cues by gluing them thereon and waiting for them to dry is overcome. When the cue is not in use by its owner, the ferrule may be removed, thus preventing its use by others not entitled to such use.

Having thus fully described our invention, what we claim, and desire to secure by Letters Patent, is—

A billiard-cue comprising a body portion 80 having a reduced tapered end, a central conical lug formed thereon, a right-angled circumferential shoulder formed on the cue by said reduction, said reduced end being screw-threaded externally, a tapered metal ferrule internally screw-threaded at its inner or larger end and having its smaller end formed with an external circumferential bevel, said ferrule being adapted to screw onto the screw-threaded end of the body portion and rest against said shoulder, and a semi-elastic tip, larger in diameter than the internal diameter of the smaller end of said ferrule adapted to be inserted into said ferrule from the larger end and to be forced partially through said ferrule, and its inner end expanded by the act of screwing said ferrule onto the body portion, said tip resting normally against the end of the body portion of the cue.

In testimony whereof we affix our signatures in presence of two subscribing witnesses.

ZIBA HICKMAN.
JOHN C. HERBINE.
